UNITED STATES PATENT OFFICE.

BENJAMIN H. PATRICK, OF MOUNT GAY, WEST VIRGINIA.

RAILROAD SWITCH.

Application filed October 19, 1926. Serial No. 142,681.

My invention relates generally to improvements in railroad switches, and it consists in the combinations, constructions and arrangements herein described and claimed.

5 An object of the invention is the provision in a railroad switch of simple, reliable and efficient means for facilitating the throwing of the switch points to either of their set positions when such switch points 10 have been moved a certain distance from their other set position, and for maintaining the switch points in either of their set positions firmly, although yieldingly.

Another object of the invention is the provision in a railroad switch of means for yieldingly maintaining the switch points in either of their set positions so that such switch points may be actuated by the flanges of wheels of a car that is passing from a 20 closed branch line through the switch onto an associated main line of the railroad so that such car may move through the switch onto the rails of the main line without injury to the switch points or to the car.

25 Other objects and advantages of the invention will be apparent from the following description, considered in conjunction with the accompanying drawings, in which

Figure 1 is a plan view of the improved switch with the switch points in one of their 30 two possible set positions,

Figure 2 is a section substantially on the line 2—2 of Figure 1,

Figure 3 is a view similar to Figure 1, 35 showing the switch points in their second set position,

Figure 4 is a perspective view of the controlling means of the improved switch, and

Figure 5 is a perspective view of a lever 40 that is used in the holding means of the improved switch construction.

In Figures 1 and 3, the numerals 1 and 2 generally designate the parallel rails of a main track and 3 and 4 generally indicate parallel rails of an associated spur track or siding. Parallel switch points 5 and 6, respectively, may be of any suitable known construction and respectively are pivotally connected at 7 and 8 in any suitable known manner with portions of the adjacent rails of the siding and the main track, respectively. The aforesaid rails, including the switch points, are supported on ties 9, as is usual. The switch points 5 and 6 are maintained in spaced parallel relation with each other by their pivotal connections with the

rails 3 and 2, respectively, of the aforesaid main track and associated siding in conjunction with a cross connecting bar 10 which extends underneath the free end portions of 60 the switch points and is connected with the switch points at 11 so that the switch points will swing horizontally in unison when the connecting bar 10 is moved longitudinally. The cross connecting bar 10 extends laterally 65 of the remote rails of the adjacent portions of the main track and the siding and has its extreme end portions curved upwardly and rearwardly at 12 for convenience of actuation by the hand or the foot of a workman 70 when it is desired to swing the switch points from the set position shown in Figure 1 to the set position shown in Figure 3, or vice versa.

The invention provides means for facilitating the movements of the switch points toward either of their two possible set positions after such switch points have been moved from one of such set positions slightly more than halfway toward the other set position. Such means includes a lever 13. The lever 13 may be a bar as shown, that is connected at one end by a vertical pivot element 14 with the cross bar 10 intermediate the switch points. The lever 13 is formed intermediate its length with a longitudinally extending slot 15. A vertical pivot element 16 is upstanding from a tie plate 17 and extends through the slot 15. A nut 18 threadedly engages the upper end portion of the pivot element 16 and retains the lever 13 in place on the tie plate so that the lever 13 is capable of limited longitudinal movement on the tie plate and may swing on the tie plate about the pivot element 16 of a fulcrum. The tie plate 17 is adapted to be engaged by railroad spikes 20 for securing the tie plate 17 firmly in place on a plurality of the ties 9 and intermediate the switch points and has a downturned end portion 19 fitting against a side of one of the ties 9 adjacent to the connecting bar 10.

The second end portion of the lever 13 is connected pivotally by a vertical pivot element 21 with a horizontal arm 23 of a right angular section 24 of a lever actuating member. Said right angular section 24 also includes an upwardly turned vertical arm 25 at the outer end of the arm 23. A rod section 26 that is included in the lever actuating member as a threaded end portion extending through an opening in the up-

turned arm 25 of the section 24 and connected adjustably with the upturned arm 25 and section 24 are a pair of clamping nuts 27. The rod 26 extends slidably through an opening 28 in the upturned vertical arm 29 of a substantially right angular bracket 30 which has a horizontal arm 31 provided with openings for the reception of fastening devices 32 for securing the arm 31 of the bracket 30 onto the tie plate 17. An expansion spring 34 of coil form is disposed on the rod 26 between the upturned vertical arm 29 of the bracket 30 and an adjusting nut 35. The adjusting nut 35 is in threaded engagement with the rod 26 and is adapted to be secured in adjusted position on the rod 26 by a lock nut 36 after the nut 35 has been adjusted to compress the spring as desired.

From the foregoing description of the various parts of the device, the operation thereof may be readily understood. The length of the lever 13 and its actuating members 24-26 combined is greater than the straight line distance between the upturned arm 29 of the bracket 30 and the point of pivotal connection of the lever 13 with the switch point connecting bar 10. The spring 34 therefore will function to normally retain the lever 13 at an oblique angle with the connecting bar 10 and the lever actuating member at an oblique angle with the lever 13. The action of the spring 34 therefore will tend to maintain the switch points in either of their two possible set positions and will snap the switch points to either of their possible set positions after such switch points have been swung slightly more than half the distance from one of their possible set positions to their other possible set position. The rod section 26 of the lever actuating means may slide in the opening 28 of the arm 29 of the bracket 30 against the action of the spring 34 sufficiently to permit the sections of the lever actuating member to swing relatively to each other about the axis of the pivot element 21 from the position shown in Figures 1 and 4 to the position shown in Figure 3 as the switch points are swung from the set position shown in Figure 1 to the set position shown in Figure 3. When the switch points are in the set position shown in Figure 1, the main track is open and railway cars may pass along the main track in either direction past the junction of the main track with the siding without actuating the switch points and without moving onto the siding. However, should a car pass from the siding toward the main track when the switch points are in the set position shown in Figure 1, the flanges of the front wheels of such car would actuate the switch points sufficiently to permit movement of the wheels of the car along the switch points onto the main track without derailment and the switch points then would

return automatically to the set position shown in Figure 1. When the switch points are in the set position shown in Figure 3, a railway car may pass on the main track from the right hand side of the sheet of drawings onto the siding or from the siding onto the main track without actuation of the switch points. Further, should the car move along the main track from the left hand side of the sheet of drawings, the flanges of the front wheels of such car will on contact with the switch points actuate said switch points to permit movement of the wheels of the car along the switch points onto the rails of the main track without derailment and without injury to the switch points or to the car, after which the switch points will return automatically to the position shown in Figure 3. It therefore will be obvious that the switch embodied in the invention will obviate accidents because of inadvertent movement of railway rolling stock in the wrong direction when the switch points are in either of their two possible set positions.

Obviously, the invention is susceptible of embodiment in forms other than that which is illustrated in the accompanying drawings and I therefore consider as my own all such modifications and adaptations thereof as clearly fall within the scope of the appended claims.

I claim:

1. In a railroad switch, the combination with a pair of pivoted switch points of a cross bar connected with the free end portions of said switch points and extending laterally on opposite sides of the associated track rails, the free end portions of said cross bar being turned upwardly to produce actuating members.

2. In a railroad switch, the combination with a pair of pivoted switch points of a cross bar connected with the free end portions of said switch points and extending laterally on opposite sides of the associated track rails, the free end portions of said cross bar being curved upwardly and rearwardly to produce actuating members.

3. The combination with a pair of horizontally swingable pivoted switch points, of a cross bar connected with the free end portions of said switch points, a lever fulcrumed intermediate its ends and swingable horizontally between said switch points and pivotally connected at one end with said cross bar, a fixed supporting member having an upturned arm provided with a horizontal opening, and a spring pressed lever actuating member comprising a section pivotally connected with the second end portion of said lever and a rod secured at one end to said section and having its opposite end portion slidably disposed in the opening of said fixed supporting member.

4. In a railroad switch, the combination with a pair of switch points of a cross bar connecting the free end portions of said switch points, a tie plate secured in place adjacent to said cross bar and between said switch points, an upstanding pivot element on said tie plate, a lever pivotally connected at one end with said cross bar intermediate said switch points, said lever having a longitudinally extending slot intermediate its length for the reception of said upstanding pivot element, a lever actuating member comprising a section pivotally connected with the second end portion of said lever and having an upturned arm, a rod adjustably secured to the upturned arm of said section, a fixed supporting member disposed in spaced relation to said upstanding arm of said section and having also an upstanding arm provided with an opening, a rod adjustably connected to the arm of said section of the lever actuating member and having a portion extending slidably through the opening of the upstanding arm of said supporting member, and an expansion spring disposed on said rod and acting on said lever actuating member to facilitate movement of said lever to either limit of its positions in opposite directions after said lever has passed an intermediate position and to yieldingly maintain the lever at the limit of its throw in either of opposite directions.
5. In a railroad switch, the combination with a pair of switch points of a cross bar connecting the free end portions of said switch points, a tie plate secured in place adjacent to said cross bar and between said switch points, an upstanding pivot element on said tie plate, a lever pivotally connected at one end with said cross bar intermediate said switch points, said lever having a longitudinally extending slot intermediate its length for the reception of said upstanding pivot element, a lever actuating member comprising a section pivotally connected with the second end portion of said lever and having an upturned arm, a rod adjustably secured to the upturned arm of said section, a fixed supporting member disposed in spaced relation to said upstanding arm of said section and having also an upstanding arm provided with an opening, a rod adjustably connected to the arm of said section of the lever actuating member and having a portion extending slidably through the opening of the upstanding arm of said supporting member, and an expansion spring disposed on said rod and acting on said lever actuating member to facilitate movement of said lever to either limit of its positions in opposite directions after said lever has passed an intermediate position and to yieldingly maintain the lever at the limit of its throw in either of opposite directions.

BENJAMIN H. PATRICK.
